TYPOGRAPHICAL COMPOSING MACHINE

John H. Hilpman, Hollis, N. Y., assignor to Mergenthaler Linotype Company, a corporation of New York

Application January 4, 1933, Serial No. 650,054

18 Claims. (Cl. 199—22)

This invention relates to typographical composing machines, such as linotype machines of the general organization represented in Letters Patent to O. Mergenthaler, No. 436,532, wherein circulating matrices and expansible spacebands are released from separate magazines by the manipulation of a keyboard and then composed in line, the composed line transferred to the face of a mold, the mold filled with molten metal to form a slug or linotype against the matrices which produce the type characters thereon, and the matrices and spacebands thereafter elevated and returned by suitable mechanisms to the magazines from which they started.

The release of the matrices is effected by a series of matrix releasing devices including a corresponding number of depressible finger keys (usually ninety in number) bearing the different characters of the corresponding matrices, whereas the release of the spacebands (which are all alike) is effected by a single blank finger key. In the commercial machines, there are usually included blank spacing matrices or quads of three different thicknesses commonly known as em, en, and thin spacers. These three different spacers are contained in the regular matrix storage magazine and are released therefrom each by the actuation of an independent finger key.

Certain classes of composition require for each line an extraordinary amount of spacing for which the spacebands alone are not adapted, and for which the spacers are used. For instance, in certain types of composition for book and advertising purposes, it is sometimes desirable to space words or portions of the lines several ems apart, or to space out one or both ends of the line to such extent that several spacers are required. At the same time, it is necessary, for purposes of justification, to compose the required number of expansible spacebands in the line, and the composition of each spacer and each spaceband requires the separate actuation or depression of a finger key. Furthermore, it may be desired at times to compose lines of matrices including several spacers without including expansible spacebands, as when a line is to be quadded out at either or both ends, or centered and quadded out.

The object of the present invention is to facilitate the composition of lines of matrices for the special classes of work referred to, and to this end, means is provided whereby the release of the em, en and thin spacers may be effected by the actuation of the spaceband releasing finger

key. More specifically, the invention contemplates the provision of three independently controlled connecting links, one for each of the spacer releasing finger keys, connected with the spaceband key and movable at will into engagement with the spacer releasing keys, whereby the latter may be connected so that when the spaceband key is actuated to release a spaceband any one or any combination of the spacer releasing keys will be actuated to release corresponding spacers. In addition, means is provided to prevent the release of a spaceband without preventing the actuation of the spaceband key, whereby the latter may be actuated to release any one or any combination of the spacers without releasing a spaceband.

In the accompanying drawings, the invention has been shown merely by way of example and in preferred form, and obviously many variations and modifications may be made therein without departing from the spirit of the invention. It is to be understood, therefore, that the invention is not limited to any particular form or embodiment, except insofar as such limitations are specified in the appended claims.

Referring to the drawings:

Fig. 1 is a front elevation of a portion of a linotype machine with the present improvements applied thereto;

Fig. 2 is a perspective view of a portion of the improved keyboard mechanism and matrix releasing devices; and

Fig. 3 is a side elevation of a portion of the keyboard mechanism, showing the connection between the spaceband releasing key and one of the spacer releasing keys.

The matrices X and spacebands Y (see Fig. 1) are stored in the respective magazines X¹, Y¹, and are released therefrom for composition in line by the regular power operated devices which constitute part of the keyboard mechanism. These devices include a series of upright reeds A, a corresponding series of vertical slides A¹, and intermediate cam yokes A², each yoke being pivotally mounted at one end in the usual manner on a pin passing through the opening A³ and having its other end sustained by means of a trip dog A⁴ connected to the corresponding slide A¹, the cam A⁵ carried by each yoke being in engaging relation to an underlying constantly driven rubber covered roll A⁶. (Ordinarily, there are two banks of cams and two rollers, arranged on opposite sides of the reeds, but to understand the present invention it is only necessary to show a

portion of this structure.) The arrangement is such that as the slides A¹ are raised, the cams A⁵ are allowed to drop into peripheral contact with the roll A⁶, and by their consequent rotation, 5 lift the yokes A² which, in turn, operate the reeds A. All of the slides A¹, except the one at the rear ends of the matrix releasing finger keys B (Fig. 1), which are disposed in rows or 10 tiers at different levels, being pivotally mounted for vertical movement on transverse rods passing through the openings B¹ in the keys B, and supported at their opposite ends by the side plates C³ and C⁴ of the keyboard C. The keyboard includes, as usual, a supporting frame C¹, the two 15 side plates C³, C⁴, the inclined front plate C⁵, and top plate C⁶.

The uppermost row or tier of finger keys B includes three keys F, F¹ and F² located centrally of the keyboard and operable through slides A¹, cams A⁵ and reeds A to release the em, en and thin spacers, respectively, from the matrix storage magazine. It is with these three 20 spacer releasing keys and associated parts that 25 the invention is particularly concerned, as will presently appear.

The actuating slide A⁷ is connected to an arm D keyed or otherwise secured to a horizontal rock shaft D¹, which extends completely across 30 the keyboard, and is journaled in the side plates C³, C⁴ thereof. The arm D is located at one end of the shaft D¹ adjacent the inner wall of the right side plate C³, and at its other end, the shaft is provided with a lever arm or finger key D², 35 located adjacent the outer wall of the left side plate C⁴. In the arrangement shown, therefore, the arm D, rock shaft D¹, and finger piece D², together constitute the spaceband releasing key, which however, may also include (as is usually 40 the case) a second finger piece or finger key attached to the shaft D at the right of the keyboard C, or even a third finger piece at the top of the keyboard in the nature of a universal bar extending entirely across the keyboard (as is also 45 frequently the case).

When the spaceband key D² is actuated, the slide A⁷ is raised by the arm D, and the reed A⁸ directly above the slide is operated in the usual way by the underlying cam yoke A². This particular reed A⁸, as may be observed (Fig. 1), is considerably shorter than the other reeds A, and is connected at its upper end by a horizontal lever D³ to the escapement actuating arm Y² of the magazine Y¹, which escapement controls the release of the spacebands Y. The lever D³ is pivotally mounted as at D⁴, and is rocked about its pivot in a counterclockwise direction when the right hand end is raised by the upward movement of the reed A⁸. A tension spring D⁵, one 55 end of which is secured to the right arm of the lever D³ and the other end of which is suitably fastened to a stationary part of the machine, serves to rock the lever D³ in a clockwise direction to return and maintain the lever, the spaceband escapement mechanism, and the reed A⁸ 60 in their normal inactive positions.

As before stated, means is provided by the present invention whereby the em, en and thin spacer releasing devices may be connected singly, 70 or collectively in any combination, to the spaceband releasing finger key for actuation thereby. In the preferred embodiment illustrated, the finger keys, F, F¹ and F² are formed rearwardly of their pivot points B¹ with slots F⁵, these slots being 75 adapted to receive pins E¹¹ protruding laterally

from the free ends of a series of connecting links in the form of crank arms E, E¹ and E² slidably mounted on the rock shaft D¹, and which pins normally occupy a position clear of but in horizontal alignment with the slots F⁵. Each of the crank arms E, E¹ and E² is formed with a slot E³ adapted to receive a pin E⁴ projecting from the shaft D¹, which pin and slot connections limit the sliding movement of the crank arms on the shaft. Connected to the respective crank arms are three rods E⁵, E⁶, and E⁷, extending toward the right and having their ends upturned to project through elongated slots E⁸ formed in the top plate C⁶ of the keyboard C, the ends of the rods being fitted with handles or knobs E⁹. In order that the rods E⁵ and E⁶ may be secured to the crank arms E and E¹, respectively, without being bent, the crank arm E¹ is formed with a groove E¹⁰ in its front edge, and the crank arm E² is formed with similar grooves in both its front and rear edges, these grooves being of sufficient size and shape to receive the rods E⁵ and E⁶ and provide enough clearance to avoid conflict between the rods and the crank arms as the latter are rocked with the shaft D¹. 80 85 90 95 100

As before stated, the free end of each of the crank arms is provided with a pin E¹¹ in horizontal alignment with the slot F⁵ formed in the adjacent one of the finger keys F, F¹ and F², controlling the release of the em, en and thin spacers. 105 When the crank arms occupy their right hand position, the pins E¹¹ are located out of engagement therewith, but when the crank arms are moved to the left, the pins enter the slots F⁵ in the finger keys and form a connection between the 110 rock shaft D¹ and the keys, whereby the latter will be actuated by the rocking movement of the shaft.

Referring to Fig. 3, wherein the relation of the parts is more clearly shown, it will be seen that 115 the slots F⁵ in the keys F, F¹ and F² are located some distance behind the openings or pivotal points B¹ of the keys, and that these slots are located to the rear (to the right in Fig. 3) of the shaft D¹, so that the depression of the spaceband 120 releasing key D², by rotating the shaft D¹ in a clockwise direction, acts through the crank arms to raise the rear portions of the keys F, F¹ and F², just as if they were actuated directly. Of course, the arrangement of the crank arms could be 125 reversed, and their connection with the keys located forward of the pivot point, so that the clockwise rocking of the shaft D¹ would act to depress the forward portions of the keys.

As already stated, means have also been provided for preventing the release of spacebands Y from their storage magazine Y¹ when it is desired to compose a line of matrices without spacebands. In the commercial machines, the spacebands Y are retained in the magazine Y¹ with the foremost 130 band in position to be released by escapement mechanism actuated by a pair of vertically movable arms Y² and Y³. The operation of the arms Y² and Y³ is effected by the spaceband key D², which, when actuated, causes the lever D³ to be 135 140 145 rocked in a counterclockwise direction, thereby permitting the arms to move downwardly and in so doing operate the escapement mechanism to release a spaceband, the parts being immediately returned to normal position by the spring D⁵, as already set forth.

According to the present invention, an interponent Y⁴ is pivotally attached to the magazine Y¹ at a point below the front arm Y³, and is provided with a handle or knob Y⁵ by which it may 150

be readily moved into and out of active position. The interponent Y^4 is shown in Fig. 1 as occupying its inactive position, in which case the actuation of the spaceband key D^2 will effect the release of a spaceband. However, when the interponent is moved into engagement with the arm Y^3 to maintain the latter in its upper or non-releasing position, the actuation of the spaceband key D^2 will operate as usual to rock the level D^3 , 5 but the interponent Y^4 will hold the arm Y^3 against downward movement and thus prevent the release of a spaceband.

It will now be clear that in the operation of the machine, if it be desired to compose in line 15 a spaceband and any one or any combination of the em, en and thin spacers, the operator, by moving the selected handle or handles E^9 toward the left, thereby connects the corresponding key or keys F , F^1 and F^2 to the rock shaft D^1 . 20 The depression of the key D^2 , through the rock shaft D^1 and whichever of the crank arms E , E^1 , or E^2 have been moved into engagement with their respective keys, will simultaneously actuate those keys, and thus simultaneously effect the 25 release of a spaceband and one or more spacers. If, on the other hand, it is desired to release any one, or any combination of the spacers, without releasing a spaceband, the interponent Y^4 may be moved into active position to prevent the operation of the spaceband escapement mechanism, 30 and hence prevent the release of a spaceband without in any way interfering with the actuation of the spaceband key D^2 .

One advantage of the present invention not 35 heretofore pointed out, and which will now be more readily appreciated, resides in the fact that the spacers may be used with or without spacebands, and in either case, the operator, who has acquired a certain rhythm of composition, merely 40 actuates the spaceband key D^2 as though to compose a spaceband, but instead composes a spaceband and one or more spacers, or the desired number of spacers alone, without having interrupted the rhythm of composition to which 45 he is accustomed.

In the embodiment shown and described, the direct connection between the spaceband key and spacer keys permits of the actuation of the latter by the former, or vice versa. In other words, the 50 actuation of all those finger keys which are connected together may be effected by the actuation of any one of the keys. Also, the spaceband releasing mechanism may be locked against operation so that spacers alone will be released 55 by the actuation of the spaceband key as well as by the spacer keys.

However, it is also within the spirit of the invention to arrange the parts so that the release of spacers and spacebands could be effected 60 by the actuation of either the spaceband key or the spacer keys, but not both. For instance, the arrangement could be such that the pins E^{11} would overlie the finger keys F , F^1 and F^2 , in which event actuation of the spacer keys would 65 operate through the crank arms E , E^1 and E^2 to rock the shaft D^1 and effect the release of a spaceband, whereas actuation of the spaceband key D^2 would move the pins E^{11} carried by the crank arms away from the spacer keys without 70 in any way affecting said keys. On the other hand, with the parts arranged so that the pins E^{11} would lie beneath the spacer keys, the latter could then be actuated by the actuation of the spaceband key without allowing the latter key 75 to be affected by the actuation of the spacer keys.

In the appended claims, the expression "matrix releasing keys", while applying primarily to the spacer keys, is also intended to embrace any other keys which it might be desirable to couple with the spaceband key. In other words, the keys could be those releasing character bearing matrices as well as those releasing blank matrices or quads which latter constitute the so-called spacers.

Having thus described my invention, what I claim is:

1. A keyboard mechanism for typographical composing machines including, in combination, a series of matrix releasing finger keys, a spaceband releasing finger key, and means whereby the spaceband releasing key may be connected directly to a selected plurality of the matrix releasing keys, said connections acting to transmit the normal actuating movement of one key to the others to bring about their conjoint 95 operation.

2. A keyboard mechanism for typographical composing machines including, in combination, a series of matrix releasing finger keys, a spaceband releasing finger key, and means whereby the spaceband releasing key may be connected directly to any selected plurality of the matrix releasing keys, said connections acting to transmit the normal actuating movement of one key to the others to bring about their conjoint 100 operation.

3. A keyboard mechanism for typographical composing machines including, in combination, a series of matrix releasing finger keys, a spaceband releasing finger key, and means whereby the spaceband releasing key may be connected directly to different selected pluralities of the matrix releasing keys, said connections acting to transmit the normal actuating movement of one key to the others to bring about their conjoint 110 operation.

4. A keyboard mechanism for typographical composing machines including, in combination, a series of matrix releasing finger keys, a spaceband releasing finger key, and means whereby the spaceband releasing key may be connected directly to a selected matrix releasing key or a selected plurality of said keys, as desired, said connections acting to transmit the normal actuating movement of one key to the others to bring 120 about their conjoint operation.

5. A keyboard mechanism for typographical composing machines including, in combination, a series of matrix releasing finger keys, a spaceband releasing finger key, and means whereby the spaceband releasing key may be connected directly to any selected matrix releasing key or any selected plurality of said keys, as desired, said connections acting to transmit the normal actuating movement of one key to the others to 130 bring about their conjoint operation.

6. A keyboard mechanism for typographical composing machines including, in combination, a series of matrix releasing finger keys, a spaceband releasing finger key, and means whereby the spaceband releasing key may be connected directly to different selected matrix releasing keys or to different selected pluralities of said keys, as desired, said connections acting to transmit the normal actuating movement of one key to the others to bring about their conjoint 140 operation.

7. A keyboard mechanism for typographical composing machines including, in combination, a frame, a series of matrix releasing finger keys pivotally mounted in said frame, a rock shaft 150

- extending at right angles to said keys and journaled in said frame, a spaceband releasing finger key for rocking said shaft, and means on said shaft adapted to be moved at will into engagement with the matrix releasing finger keys, whereby the actuation of the spaceband releasing key in rocking said shaft will effect the actuation of the matrix releasing finger keys connected therewith. 80
- 10 8. A keyboard mechanism as set forth in claim 7, wherein the means for connecting the pivotally mounted keys to the rock shaft comprises a plurality of crank arms secured to the shaft and provided each with a pin adapted to engage in a slot formed in the key with which it is associated. 85
- 15 9. A keyboard mechanism as set forth in claim 7, wherein the means for connecting the pivotally mounted keys to the rock shaft comprises a plurality of independently controlled crank arms slidably mounted on the shaft and provided each with a pin adapted to engage in a slot formed in the key with which it is associated. 90
- 20 10. A keyboard mechanism as set forth in claim 7, wherein the means for connecting the pivotally mounted keys to the rock shaft comprises a plurality of crank arms slidably mounted on the shaft and provided each with a pin adapted to engage in a slot formed in the key with which it is associated, and control means for the crank arms whereby any one or any combination of the series of finger keys may be connected for actuation by the rotation of the rock shaft. 95
- 25 11. A keyboard mechanism for typographical composing machines, including, in combination, a series of matrix releasing finger keys, a spaceband releasing finger key, and means for connecting one or more of said matrix releasing keys positively to the spaceband key, whereby the actuation of the spaceband releasing key will effect the actuation of the connected matrix releasing key or keys, or vice versa. 100
- 30 12. In a typographical composing machine, the combination of a magazine having a supply of spacebands, means for retaining the spacebands in the magazine, means operable to effect the release of the spacebands from the magazine, means for actuating said releasing means, and means to prevent the operation of said releasing means without preventing the action of said actuating means. 105
- 35 13. In a typographical composing machine, the combination of a magazine having a supply of spacebands, means for retaining the spacebands in the magazine, means operable to effect the release of the spacebands from the magazine, means for actuating said releasing means, and means to prevent the release of a spaceband from the magazine, a spaceband releasing finger key for actuating said releasing means, and an interponent movable into position to engage with and prevent the operation of said releasing means without preventing the depression of the finger key. 110
- 40 14. In a typographical composing machine, the combination of an independently operable matrix releasing device, an independently operable spaceband releasing device, and means for positively connecting the matrix releasing device with the spaceband releasing device, whereby the operation of either of said devices will effect the operation of both. 115
- 45 15. In a typographical composing machine, the combination of a series of independently operable matrix releasing devices, an independently operable spaceband releasing device, and means for positively connecting a plurality of the matrix releasing devices with the spaceband releasing device, whereby the operation of any one of said connected devices will effect the operation of all. 120
- 50 16. In a typographical composing machine, the combination of a plurality of independently operable matrix releasing devices, an independently operable spaceband releasing device, means for effecting the operation of any one of said plurality of matrix releasing devices by the operation of the spaceband releasing device, and means to prevent the release of a spaceband when the spaceband releasing device is operated. 125
- 55 17. In a typographical composing machine, the combination of a plurality of independently operable matrix releasing devices, an independently operable spaceband releasing device, means for effecting the simultaneous operation of any one or more of said plurality of matrix releasing devices by the operation of the spaceband releasing device, and means to prevent the release of a spaceband when the spaceband releasing device is operated. 130
- 60 18. In a typographical composing machine, the combination of a plurality of independently operable matrix releasing devices, an independently operable spaceband releasing device, independent means for connecting each of said matrix releasing devices to the spaceband releasing device, whereby any individual matrix releasing device or any combination of said plurality of matrix releasing devices may be connected to the spaceband releasing device for operation thereby, and means to prevent the release of a spaceband by the operation of the spaceband releasing device. 135
